ENVELOPE FOR AN ELECTRIC DEVICE

Clayton T. Ulrey, East Orange, N. J., assignor, by
mesne assignments, to Westinghouse Electric
and Manufacturing Company, East Pittsburgh,
Pa., a corporation of Pennsylvania

Application November 1, 1933, Serial No. 696,180
Renewed February 18, 1937

12 Claims. (Cl. 250—35)

The invention relates to electric devices, especially to an improved envelope therefor, and also to a new method for producing the same. In its more specific aspect the invention is directed to a 5 novel envelope for a radiation producing electric device, and to the method for producing the same.

Although my invention is not limited to the X-ray field it will be described with reference to an X-ray tube because it finds immediate and 10 especial application as an element thereof. X-ray tubes generally comprise an anode and a cathode located within a vitreous highly evacuated envelope. The envelope may be in the form of a cylinder having a small portion thereof which is 15 thinner than the remaining portion of said envelope. This thin section is customarily of rectangular or curved contour, with the length of the section being equal to about one-fourth the circumference of the tube. The methods heretofore 20 employed for rendering said section thinner than the remainder of the envelope involve the employment of an etching solution or a mechanical abrasive means. Both of these methods have inherent difficulties.

25 In both cases the forming of the window is a relatively slow and time-consuming task. The first method has the additional disadvantage in that an appreciable percentage of the envelopes is broken during this procedure of grinding to 30 form a window. In order to obviate the above enumerated, as well as other disadvantages inherent in, and incidental to, the methods above outlined and, so that a novel type of window may be provided, I have developed the present invention.

35 Briefly, the invention comprises an envelope having a portion thereof in the form of a band extending entirely around the circumference thereof and measuring in thickness a great deal less than the remainder of the envelope and being 40 of the same composition as the remainder of said envelope. The novel envelope is produced by heating a restricted band of said envelope and applying tension thereto to thin out the same at that restricted area.

45 An object of my invention is to provide an envelope having a thin window which envelope may be readily and inexpensively produced.

Another object of my invention is to provide 50 an electric discharge device having an envelope with a thin window which thin window may be produced by an unskilled operator.

Still another object of my invention is to provide 55 a new method for producing an envelope with a thin window.

Other objects and advantages of my invention will be readily apparent from the following description and drawing wherein,

Figure 1 illustrates an X-ray tube embodying 5 my invention;

Figure 2 represents an enlarged cross sectional view taken on line II—II of Figure 1;

Figure 3 illustrates the means employed at one 10 step of my novel process;

Figure 4 is a cross sectional view taken on line 15 IV—IV of Fig. 3;

Figure 5 illustrates the means employed at a 20 later step of my invention and also illustrates the condition of the envelope at this stage;

Figure 6 is a cross sectional view taken on line 25 VI—VI of Figure 5.

As shown in Figure 1, the X-ray tube embodying 30 my invention comprises an envelope 9 having an anode 10, and a cathode 12 therein. The envelope 9 is air-tight and is composed of a vitreous dielectric material, such as glass. The envelope 9 has a body portion 11 which is in the form of an elongated cylinder. Extending into said cylinder 11 and sealed thereto by fusion is a glass reentrant stem 13 having a pinch or press 14 at the free end 35 thereof. Sealed in said press 14 are a plurality of conductors 15, 16 and 17 connected to the cathode 12. The conductors 15 and 16 extend exteriorly, as well as interiorly, of the envelope 9. A reentrant tube 18 is sealed by fusion to the other end 40 of the cylinder 11 and extends a short distance therein. A copper thimble 19 having its rim sealed to the free end of the tube 18 forms an air-tight hermetic seal therewith. The anode 10 and an anode extension 20 carrying a heat radiator 21 are 45 connected, as shown, to the thimble 19. Another reentrant tube 22 is ring-sealed to the inner wall of the cylinder 11 and surrounds the anode 10. A spring member 23 is secured to the anode and frictionally engages the interior surface of the tube 22 to aid in supporting the anode 10.

According to my invention the body portion of 50 the envelope 9, which is in the form of a cylinder, has a section 30 thereof whose thickness is materially less than that of the remainder of the envelope so that the absorption of this section to radiations below the visible portion of the spectrum is materially less than that of the remainder of the envelope. As shown, the thickness of the band 55 30 is about one-third the general thickness of the remainder of the envelope. Of course, it is within the purview of my invention to have the band 30 of any desired thickness depending upon what I desire.

Although it is not absolutely essential to my invention, I prefer that the outer diameter of the section 30 shall be substantially the same as the outer diameter of the major portion of the cylinder 11. The thin band 30 is located opposite the free or target end of the anode 10 and the width of said band which may be of any desired magnitude is so chosen that most of the useful X-rays generated at the target may pass there-10 through.

The X-ray tube heretofore described is assembled in the manner well known in the art. However, the novel step in the manufacture of the X-ray tube, and which is essentially a portion 15 of my invention, is directed to the formation of a band window in the body portion of the envelope.

According to my invention the vitreous cylinder 11 that is to form the body portion of the envelope 20 is placed between a pair of chucks (diagrammatically shown in Figure 5) of a glass lathe. The jaws of said chucks tightly grip the ends of said cylinder 11 and are adapted to rotate in synchronization with each other and thus properly rotate the cylinder 11. A pair of bands 31 and 32 composed of a highly refractory dielectric (asbestos) or other material are inserted over the cylinder 11 in proper position and are spaced the desired distance apart. A plurality of nozzles 33 25 are spaced from and located around the periphery of the cylinder between the bands 31 and 32. A suitable gas or admixture of gases pass through said nozzles. These gases are ignited to produce flames which play directly upon that portion of the cylinder 11 between the bands 31 and 32 which serve as a baffle to limit the heating of the glass to a particular area. The cylinder 11, together with the baffles, is continuously rotated during the period that the gas flames strike the glass to 30 heat and soften the same. After the glass between the baffles has been heated to the desired extent and has become sufficiently softened, the chucks are moved away from each other thus drawing the softened glass band between the baffles 31 and 32.

Throughout the drawing stage the cylinder 11 is continually rotated and the intensity of the flames may be reduced, but they are played upon said band 30 during this action. I have found 50 that when the glass has become softened due to its elevation in temperature at the band portion thereof, and after drawing, that the glass at the band portion 30 recedes inwardly towards the central longitudinal axis of the cylinder. To rectify this phenomenon I have provided one end of the cylinder with a tightly fitting rubber stopper 34 and the other end of the cylinder with a rubber stopper 35 through which extends a tubular element 36 adapted to convey an inert gas, such as nitrogen, into said cylinder. During the period that the band is being drawn and immediately thereafter a gas, such as nitrogen, is forced under pressure into said cylinder through the element 36. The glass still being in a rather soft condition at the drawn band portion thereof is blown outwardly due to the gas pressure which I have created within the cylinder 11. Of course the gas pressure is so regulated that the softened 60 band is not blown out to a large bubble.

A tool 37 having a flat plate 38 at one end thereof may be placed upon the cylinder and over the softened band of the glass so that as the pressure within the cylinder is built up it will merely force 75 the softened glass out only as far as the outer

surface of the cylinder 11. Thus the band 30 may be made thinner than the remaining portion of the envelope and may have the same outside diameter as the remainder of the envelope. Thereafter, of course, the cylinder 11 is dismounted 5 from the chucks and the customary tube assembly takes place.

As a specific example, I have taken a glass cylinder whose wall thickness measured about one hundred mils and heated a section 30 measuring about one-half inch in width. When the section 30 was sufficiently softened, the ends of the cylinder were pulled away from each other until the width of the section 30 measured about an inch and a half. During the drawing operations a 10 gas pressure was created within the cylinder to force the section 30 in proper position so that its 15 external diameter was the same as that of the remainder of the envelope.

Although my invention has been described with 20 some particularity it is not to be limited thereby but is to be limited only by the prior art.

What is claimed is:

1. In combination with a plurality of electrodes, of a vitreous envelope, a portion of said envelope being relatively thin as compared to the remainder of said envelope, said portion being homogeneously united with the remainder of said envelope and having a materially lower absorption to radiations below the visible portion of the spectrum than does the remainder of said envelope, said portion extending around the entire circumference of said envelope.

2. The combination of a plurality of electrodes with a vitreous envelope, said envelope having a portion thereof in the form of a band which is relatively thin as compared to the remainder of said envelope and which has a materially lower absorption to radiations below the visible portion of the spectrum than does the remainder of the envelope, said band extending around the entire circumference of said envelope.

3. The combination of a plurality of electrodes with a vitreous envelope, a portion of said envelope intermediate the ends thereof being relatively thin as compared to the remainder of said envelope and having a materially lowered absorption factor to radiations below the visible portion of the spectrum than does the remainder of the envelope, said portion extending around the entire circumference of said envelope.

4. The combination of a plurality of electrodes with a vitreous cylindrical envelope of substantially the same diameter throughout most of its length, a portion of said envelope being in the form of a relatively thin band and having a materially lower absorption to radiations below the visible portion of the spectrum than does the remainder of the envelope, said portion extending around the entire circumference of said envelope.

5. The combination of a plurality of electrodes with a vitreous envelope, a section of said envelope being relatively thin as compared to the remainder of said envelope, one of said electrodes having an active portion, said section being located opposite said active portion of one of said electrodes and having a materially lower absorption to radiations below the visible portion of the spectrum than does the remainder of the envelope, said portion extending around the entire circumference of said envelope.

6. The combination of a plurality of electrodes with a vitreous envelope, a portion of said envelope being relatively thin as compared to the

remainder of said envelope and having a materially lower absorption to radiations below the visible portion of the spectrum than does the remainder of the envelope, said portion extending

5 around the entire circumference of the envelope, the outside diameter of said envelope being substantially constant throughout the greater part of its length.

7. In an X-ray tube the combination of a plurality of electrodes with a vitreous envelope, a portion of said envelope being relatively thin as compared to the remainder of said envelope, one of said electrodes having a target end, said portion having a materially lower absorption to X-radiation than does the remainder of the envelope, said portion extending around the entire circumference of said envelope and being located substantially opposite the target end of said electrode.

10 8. In an X-ray tube, the combination of an anode and a cathode with a vitreous tubular envelope, a portion of said envelope intermediate the ends of said envelope being in the form of an annular, relatively thin band, said band having a materially lower absorption to X-radiation than does the remainder of the envelope, said anode having a target end, said band being located substantially opposite said target end.

15 9. In an X-ray tube, the combination of an anode and a cathode with vitreous envelope, the body portion of said envelope being in the form of a cylinder, a portion of said cylinder being relatively thin as compared to the remainder of said cylinder, said portion having a materially lower absorption to X-radiation than does the remainder of the envelope, said portion

extending around the entire circumference of the envelope, the outside diameter of said portion being substantially the same as that of the remainder of said cylinder.

10 10. Steps in the method of forming an envelope for an electric device comprising heating a complete circumferential section of a vitreous hollow member, said section being located intermediate the ends of said member, applying pressure to the interior surface of said heated section to force the same outwardly and drawing said heated section to reduce the thickness of the same.

15 11. Steps in the method of forming an envelope for an electric device comprising applying a heating flame to a section of a hollow vitreous member intermediate the ends of said member to elevate the temperature of said section for softening said section, rotating said member during the heating, drawing said section to reduce the thickness of the same and applying a fluid pressure to the interior wall of said heated section to blow out the same.

20 12. A step in the method of forming an envelope for an electric device comprising directing a plurality of flames to a section of a hollow, cylindrical, vitreous member, said section being located between the ends of said member, baffling said flames to control the width of the section to be heated by said flames, rotating said member during the heating, drawing said section to reduce the thickness of the same, applying a gas pressure to the interior wall of said section to blow the same outwardly and controlling the diameter of the external wall of said section when the same is being blown outwardly.

25 30 35 CLAYTON T. ULREY.
